(Cl. D87—3)

To all whom it may concern:

Be it known that I, Herbert S. Chase, a citizen of the United States of America, residing in New York city, county of New York, and State of New York, have invented a new, original, and ornamental Design for an Automobile Accessory Kit or Similar Article, of which the following is a specification, reference being had to the accompanying drawing, forming part thereof, wherein:

Figure 1 is a front elevational view of an automobile accessory kit or similar article, showing my new design in closed position.

Figure 2 is a side elevational view.

Figure 3 is a rear elevational view.

Figure 4 is an inner open view thereof, drawn to a smaller scale, and

Figure 5 is a view similar to Figure 4 showing the side flap members in closed position.

I claim:

The ornamental design for an automobile accessory kit or similar article, substantially as shown.
